UNITED STATES PATENT OFFICE

HERBERT G. KAMRATH, OF FLINT, MICHIGAN. ASSIGNOR TO A C SPARK PLUG COMPANY, OF FLINT, MICHIGAN, A COMPANY OF MICHIGAN

AIR CLEANER

Application filed August 3, 1927. Serial No. 210,425.

This invention relates to air cleaners of the type employed on internal combustion engines to clean the air supplied to the cylinders.

5 It is an object of the present invention to provide an air cleaner which retains all the advantages of previous constructions but which is simpler in construction and is composed of a minimum number of parts. One 10 of the features of my invention resides in providing a two part cleaner and connecting it to the carburetor inlet pipe in such a way that the inlet pipe functions as a part of the cleaner.

15 Other objects of the invention will appear in the course of the following description, taken in connection with the accompanying drawing and appended claims.

In the drawing:

20 Figure 1 is a side elevation, with parts broken away and in section, showing one form of my air cleaner connected with the intake conduit of a carburetor.

Figure 2 is an end view of the air cleaner 25 shown in Figure 1.

Figure 3 is a fragmentary bottom view of the structure shown in Figure 1, with parts broken away to show the connection between the cleaner and the air intake conduit of the 30 carburetor.

Figure 4 is a fragmentary section taken on the line 4—4 of Figure 1.

Figure 5 is a side elevation of a modified form of my invention.

35 Figure 6 is an end view of the air cleaner shown in Figure 5 taken in the direction indicated by the line 6—6 of Figure 5.

Referring particularly to Figures 1 to 4 of the drawing, the numeral 10 indicates the 40 air intake conduit of a carburetor 12 and the numeral 14 the riser leading from the carburetor to the intake manifold of an internal combustion engine.

The reference character 15 indicates my 45 improved air cleaner which consists of two parts, a body or housing 18 which is substantially frusto-conical in shape and a vane plate or cover 20. The smaller end of the body 18 is extruded to form a neck 21 which 50 is then slotted longitudinally. The portions

of the neck on opposite sides of the longitudinal slot are partially severed from the main portion thereof as indicated at 22 and then bent outwardly to provide two parallel ears 24. In the side wall of the body, 55 adjacent its smaller end there is provided a tangentially arranged dirt discharge opening 28.

On the larger end of the body 18, there is provided an outwardly extending flange 30 60 over which the outer edges of the vane plate 20 are crimped as indicated at 32 to secure the vane plate to the body. Between its circumference and its center the vane plate 20 is provided with a series of inwardly directed vanes 34 and adjacent openings 35. 65

The air cleaner 15 is adapted, as shown in the drawing, to be secured to the carburetor 12, with the collar 21 surrounding the intake conduit 10 and abutting at its outer 70 end against an annular flange or collar 16 provided on the carburetor adjacent the inner end of the intake conduit, by means of a bolt 26 which extends through perforations in the ears 24 and clamps the collar tightly 75 around the conduit 10. It will be noted that when the carburetor and the air cleaner are assembled as described above the intake conduit 10 extends into the interior of the body of the air cleaner some distance beyond the inner end of the dirt discharge 80 opening 28.

The air cleaner heretofore described operates as follows:

When the engine is operating the suction produced in the cylinders thereof causes air to be drawn into the body of the air cleaner through the openings 35 in the vane plate 20. As the air enters the body of the cleaner through the openings 35 it impinges 85 against the vanes 34 which impart to it a rotary motion. The centrifugal force of this whirling current of air which is augmented, as the air travels from the inlet to the discharge end of the cleaner, due to the 90 shape of the body, causes the foreign matter therein to be thrown to the outside of the current and against the inner walls of the body. The outer portion of the whirling current of air and the particles of for- 95 100

5 eign matter carried thereby pass into the annular space between the air intake conduit 10 and the walls of the body whence the foreign matter therein and a portion of the air passes out of the body through the dirt discharge opening 28 and whence the remainder of the air, which is free from particles of foreign matter, reverses its direction of flow, passes over the outer end of 10 the conduit and is drawn thereinto by the engine suction. From the conduit 10 the air passes into the body of the carburetor and the cylinders of the engine.

15 In Figs. 5 and 6 of the drawing the reference character 48 indicates an air cleaner which consists of a cup-shaped body portion 58 and a vane plate 56. Adjacent the closed end of the body portion there is provided a tangential dust discharge opening 62, and 20 on the open end thereof an outwardly projecting circumferential flange 60. The vane plate 56 is similar to the vane plate 20, (see Figs 1 to 4) except that there is provided in the central portion of the vane plate 56 25 an air discharge opening surrounded by an outwardly projecting neck 54, on which is provided means similar to those provided on the neck 21 (see Figs. 1 to 4) for securing the air cleaner to the air intake conduit 50 30 of a carburetor, and has its circumferential edge portions crimped over the outwardly projecting flange 60 on the open end of the body portion 58 as indicated at 61.

35 The air cleaner shown in Figs. 5 and 6 is adapted to be secured to the air intake conduit of a carburetor by means of a bolt 52, as shown in the drawing. During operation of the engine the suction produced in the engine cylinders causes air to be drawn into 40 the body portion of the air cleaner through the openings in the vane plate 56. As the air enters the body of the cleaner through the openings in the vane plate it impinges against the vanes which impart to it a 45 rotary motion. The whirling column of air passes to the closed end of the body portion of the air cleaner, whence, due to centrifugal force, the particles of dirt carried thereby are thrown out of the cleaner through the 50 dust discharge opening 62. The air which is thus freed from foreign matter reverses its direction of flow and returns to the opposite end of the air cleaner, whence it passes through the air discharge opening and air intake conduit of the carburetor into the carburetor and the engine cylinders.

55 Though I have shown and described preferred embodiments of my invention, it is to be understood that this has been done 60 merely by way of example and not with the intention of limiting the scope of my invention thereto, and that the scope of my invention is limited only by the appended claims:

65 I claim:

1. In an air cleaner, a body portion having therein air inlet and discharge openings, a neck surrounding said air discharge opening and formed integrally with and extending outwardly from the body portion, said neck being slotted so as to form thereon ears, and perforations in said ears through which a bolt is adapted to extend to secure the air cleaner to a conduit.

2. In an air cleaner, a body portion having therein air inlet and discharge openings, means to cause the air within the interior of the body portion to travel in a helical path, said air cleaner being adapted to be detachably connected to an air intake conduit, 70 which, when it is connected to the air cleaner, extends into the interior of the body portion through the air discharge opening therein and is spaced within the interior of the body portion from the side walls thereof 80 so as to provide within the interior of the body portion a dust trap, and a dirt discharge opening in the body portion adjacent the conduit.

3. In an air cleaner, a body portion having therein air inlet and air discharge openings, means to cause the air within the interior of the body portion to travel in a helical path, said air cleaner being adapted to be connected to an air intake conduit, 90 which forms a part of a device to be supplied with air, which, when it is connected to the air cleaner, extends into the interior of the body portion through the air discharge opening therein and is spaced within the 100 interior of the body portion from the side walls thereof so as to provide within the interior of the body portion a dust trap, and a dirt discharge opening in the body portion between the outer end of the conduit 105 and the air discharge opening.

4. In an air cleaner, a body portion having therein air intake and air discharge openings, a neck surrounding the air discharge opening and extending outwardly 110 from the body portion, said air cleaner being adapted to be connected to an air intake conduit, which forms a part of a suction-operated carburetor, which, when it is connected to the air cleaner, extends through 115 the neck into the interior of the body portion thereof and is spaced within the interior of the body portion from the side walls thereof so as to provide within the interior of the body portion an annular dust trap, 120 means to cause the air within the interior of the body portion to travel in a helical path from the air intake opening to the air discharge opening, and a dirt discharge opening adjacent the outer end of the air 125 intake conduit.

5. In an air cleaner, a cup-shaped body portion having in one end thereof an air discharge opening, a neck surrounding the air discharge opening and extending out- 130

wardly from the body portion, said air cleaner being adapted to be detachably connected to an air intake conduit which forms a part of a suction-operated carburetor, which, when it is connected to the air cleaner, extends through the neck and therebeyond into the interior of the body portion of the air cleaner and is spaced within the interior of the body portion from the side walls thereof so as to provide within the body portion a dust trap, means on the neck detachably to secure the air cleaner to the conduit, means including a vane plate secured over the open intake end of the body portion to cause the air passing through the interior of the body portion to travel in a helical path from the air intake end to the air discharge end thereof, and a tangential dirt discharge opening in the side wall of the body portion opposite the outer end of the air intake conduit.

6. In an air cleaner, a frusto-conoidal-shaped body portion, in the smaller end of which is provided an air discharge opening and adjacent the larger end of which is provided an air intake opening, means to cause the air passing through the interior of the body portion from the air intake opening to the air discharge opening to travel in a helical path, said air cleaner being adapted to be connected to an air intake conduit, which, when it is connected to the air cleaner, extends into the interior of the body portion through the air discharge opening therein and is spaced within the interior of the body portion from the side walls thereof so as to provide within the interior of the body portion a dust trap, and a dirt discharge opening in the body portion adjacent the conduit.

7. An air cleaner in the form of a shell contracted at one end to fit around the intake tube of a carburetor with a portion of said intake tube projecting into said shell to form an annular dust chamber, said shell at its opposite end having means for setting up a whirling motion of the air drawn into said shell, and said shell adjacent its contracted end having a peripheral dust discharge passage.

8. An air cleaner comprising a truncated conical shell provided at its smaller end with a contracted annular flange adapting it to be telescoped onto the air intake tube of a carburetor with a portion of said intake tube projecting into said shell to form an annular dust chamber, said dust chamber having a peripheral dust discharge passage adjacent its annular flange, and said shell at its larger end having a diaphragm formed with a centrally located imperforate portion and surrounding said imperforate portion having circumferentially spaced oblique vanes arranged to set up a whirling motion of the dust-laden air thrown into said shell.

9. The structure defined in claim 7 in which the dust discharge passage of said shell is formed in an outwardly pressed portion of the shell leading thereto.

In testimony whereof I affix my signature. 70
HERBERT G. KAMRATH.
